UNITED STATES PATENT OFFICE.

RICHARD PEALE, OF ST. BENEDICT, PENNSYLVANIA, ASSIGNOR, BY MESNE ASSIGNMENTS, TO REMBRANDT PEALE, W. SANDERS DAVIES, AND WILLIAM S. WALLACE, TRUSTEES.

CONVEYER.

Original application filed March 12, 1920, Serial No. 365,208, Patent No. 1,433,906, dated October 31, 1922.
Divided and this application filed December 30, 1921. Serial No. 525,832.

The invention relates to a conveying mechanism, which in certain respects is especially adapted for use in mining work.

Objects and advantages of the invention will be further set forth in part hereinafter, and in part will be obvious herefrom, or may be learned by practice with the invention, the same being realized and attained through the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a top plan of one embodied form of the invention, wherein the machine is provided with motive power additional to the conveyer;

Fig. 2 is a side elevation of Fig. 1;

Fig. 3 is an enlarged fragmentary vertical section taken on the line 3—3 of Fig. 1;

Fig. 4 is an enlarged, fragmentary vertical section, taken on line 4—4 of Fig. 1;

Fig. 5 is an enlarged, fragmentary elevation of the right hand end of Fig. 2 with a part of the gear casing cut away to show the gears and clutches within;

Fig. 6 is an enlarged fragmentary top plan corresponding to Fig. 5, and showing the driving connections with the top casing removed;

Fig. 7 is an enlarged fragmentary top plan of the upper right corner of Fig. 1, showing the opposite ends of the shafts and rollers from those shown in Fig. 6; and

Fig. 8 is an enlarged fragmentary section on line 8—8 of Fig. 6.

This application is a division of an application which has matured into Patent No. 1,433,906, granted Oct. 31, 1922.

An object of the invention is the expeditious and economical conveyance away from the working face of entries or headings, rooms, and other working faces of mines, of dislodged coal. With this main object

in view, the invention provides a conveyer or conveying means, which in accordance with certain features of the invention is auto-motived, and is capacitated to run or travel into a bottom kerf or undercutting prior to the shooting-down or other dislodgment of the coal and is also capacitated for loading and conveying away dislodged coal lying upon the mine bottom, that is, which has been "shot down" or otherwise dislodged without preliminarily placing the conveyer therebeneath. In connection with the foregoing, there is provided a plurality of attachable and detachable trucks or buggies adapted in succession to be attached to the conveying machine in order to receive a load or filling of coal therefrom, then to be detached or pushed away to a place of discharge, another truck or buggy coming into such receiving relation with the conveyer, the operation of the conveyer being thus maintained or preserved in continuity.

One feature of the invention consists in the endless conveyer belt being capacitated to constitute not only the conveying means for the coal or other loose material, but also the auto-motive means of the conveyer mechanism.

In accordance with one feature of the invention an endless conveyer is provided adapted to operate by engagement with the floor or ground as a traveling or conveying means for the entire machine, or to operate as a conveyer when the machine is at rest. The invention has also in view auto-motive means for quickly and easily turning and maneuvering the machine within small compass, and also provides means for controlling independently of each other the starting, stopping and direction of motion of the conveyer and the separate auto-motive devices.

Other objects and features of the invention other than those referred to above will appear hereinafter without particular mention at this point. It will be understood also that certain features of the invention are adapted for use independently from other features with which they are herein shown and described as in cooperation or combination, and other features of the invention

which are separately shown herein may be used together in cooperation or combination.

In accordance with certain features of the invention, independent auto-motive means in addition to or in place of the endless conveyer belt are provided. Thereby the machine may be traveled and the conveyer belt simultaneously run each independently of the direction of the other. With such independent auto-motive means, the machine is able to turn and maneuver easily and quickly, and within a very small area or radius, and is especially capacitated for attacking and conveying away piles of loose material resting upon the floor. That is, the machine is capacitated to be run into the under-cutting and to receive the falling coal thereon, or to attack a pile of coal resting on the floor or bottom. Means are provided in connection with the foregoing for controlling the movement of, and for starting and stopping and reversing the direction of movement of both the conveyer and the traction or auto-motive means each independently of the others.

Referring now more in detail to the embodied form, the endless conveyer 8 is supported in the machine in any suitable manner. As shown it runs between the vertically projecting side frames or plates 9 and 10. At its forward end it is shown running over idle rollers 12, mounted on a shaft 15. The endless conveyer is supported or backed on plates 4 extending from the side frames, and upon one or more longitudinally extending strips 13 and 14, supported on the frame, one support 11 being shown, embracing shaft 15 in Figs. 1 and 3. The conveyer passes over elements 4 and 13 of the frame, and under elements 5 and 14 thereof. The conveyer is shown conventionally, and may be of any suitable form such as that shown in the Patent 1,433,906 mentioned above.

The traction or auto-motive means as embodied constitute two endless traction treads 80 and 81 at either side of the endless conveyer 8, the conveyer and each of the treads, respectively, having its own driving connections and motion and direction controlling devices, all operable by the attendant of the machine.

In the embodied form thereof (see especially Fig. 6, and also Figs. 1 to 8), a motor 82 is suitably mounted on the machine frame, and has a bevel gear 83 fixed upon its shaft. Loosely journaled on a shaft 84, mounted in the machine frame, are two bevel gears 85 and 86, which mesh with the gear wheel 83 on opposite sides thereof, so as to be driven thereby in opposite directions. These serve to drive both the treads and the conveyer. Means are provided for driving shaft 84 in either direction, and as embodied a clutch member 87 is splined on the hub 91 of a gear wheel 92, which hub

is loosely sleeved on the shaft 84. Clutch member 87 is movable into and out of clutching engagement with the hub of bevel gear 85. An actuating handle or lever 88 is provided therefor (Figs. 1, 6 and 8) suitably pivoted on the machine frame. The lever 88 is provided with a cam roller 89 (Fig. 8) working in an annular groove 90 (Figs. 6 and 8) in the clutch member 87. The construction of the actuating means for the other clutch members is the same or similar and the foregoing description will suffice therefor. Thus when clutch 87 is moved into engagement with bevel gear 85, gear wheel 92 is driven in the same direction as bevel gear 85.

A similar construction is provided in connection with bevel gear 86 and a gear wheel 96. That is, a clutch member 93 is splined on the hub 95 of a gear wheel 96, the hub 85 being sleeved loose on shaft 84. Clutch member 93 is movable into and out of engagement with the hub of bevel gear 86. An actuating lever 94, like lever 88, is provided for throwing the clutch member 93 in and out. Thus when clutch member 93 is moved into engagement with bevel gear 86, gear wheel 96 will be driven in the opposite direction from that in which gear wheel 92 will be driven through clutch 87.

The endless conveyer 8 is preferably driven from one end thereof, and may have a drive and driving connections the same or similar to those already shown and described, although a plain conveyer and driving and guiding rollers are shown in Figs. 6 and 7 for the sake of clearness and simplicity. The driving means, shown here merely as a roller 98, journaled in the side plates 1 and 2 of the frame, has its shaft 99 fitted with driving connections which cooperate selectively or alternatively with the gear wheels 92 and 96 already described.

As embodied, a gear wheel 100 is loose on shaft 99 and meshes with gear wheel 92. A clutch member 101 is splined on shaft 99 and is movable into and out of engagement with the hub of gear wheel 100. A lever 102 operates clutch member 101 (Figs. 1 and 6).

On the opposite side a gear wheel 103 is loose on shaft 99 and is in mesh with gear wheel 96. A clutch member 104 is splined on shaft 99 and is movable into and out of engagement with the hub of gear wheel 103. A lever 105 operates clutch member 104 (Figs. 1 and 6).

With the foregoing-described mechanism, by alternatively throwing in clutch 87 or 93, the motor will either drive gear wheel 92 in one direction or gear wheel 96 in the opposite direction. Through the alternative operation of clutches 101 or 104, the conveyer 8 may be driven in either one direction or the other, as desired, and when both

clutches 101 and 104 are out, the conveyer 8 is at rest, whether either clutch 90 or 93 is in or whether they are both out. This provides means for running the conveyer in either direction, or for keeping it at rest while the motor is driving the traction means.

Means are provided for driving the endless belt treads 80 and 81 either together, 10 or in opposite directions from one another, or to drive either tread in either direction while the other is at rest, or to leave both treads at rest, and to operate the treads as just described either with or independently 15 of the operation of the endless conveyer 8.

In the embodied form, and referring first to the construction of the treads themselves as here embodied, the tread 80 and 81 comprise plates or treads proper 110, running 20 on plates or supports 111, formed in the side frames 1, 2 and 112 of the machine. The plates 110 are connected together in suitable manner, as by one or more endless 25 cables 113, which are fastened to the plates by suitable means such as clamping plates 113^a, bolted to the inside of the plates 110.

At each end the endless belt treads run respectively over sprocket wheels 114, the 30 teeth 115 of which engage with depressions 116 formed in the inner side of the plates 110. The sprocket wheels are shown in Fig. 4 formed double at each end of each of the treads. At one end of the machine, the sprocket wheels 114 are preferably or 35 conveniently idlers, and those at the opposite end of the machine are driven.

In the embodied form of drive for the endless belt tread, having the functions and capacities described in a preceding paragraph, a shaft 120 is loosely journaled in a hub 121 of one of the pair of sprocket wheels 114 (Fig. 4), the hub 121 serving as a journal for the sprocket wheel 114 in the frame 1. A stub shaft 122 is within and is fastened to the sprocket wheel and has a bearing in the frame plate 112 at the opposite side.

On the hub 121 of the sprocket wheel 114 (shown in Fig 4) is formed one clutch member 123 and the cooperating clutch member 124 is splined on shaft 120 to turn therewith while being slidable therealong into and out of engagement with clutch member 123. The opposite end of shaft 120 (Fig. 7) has the sprocket wheel 114 at the opposite side of the machine fixed thereto, the shaft being journaled in the machine frame.

A shaft 123 is journaled in the machine frame (Figs. 6 and 7) while being longitudinally slidable. On one side, shaft 128 has fixed thereto a gear wheel 130 which, as shaft 128 is moved longitudinally, passes into and out of mesh with a gear wheel 131, which is fixed on shaft 120. At its opposite

end, shaft 128 is journaled in the machine frame and in a bracket 132. Fixed on shaft 128 is a gear wheel 133 which passes into and out of engagement with gear wheel 100, as shaft 128 is moved longitudinally.

The control for clutch 123, 124, as embodied, is operated from shaft 128. A sleeve 135 is fixed between collars 136 and 137 on shaft 128 (Fig. 6), and fixed to sleeve 135 is an arm 138 terminating in a yoke 139, which yoke straddles and engages with an annular groove 140 formed in clutch member 124. Thus as shaft 128, is moved longitudinally in one direction or the other, clutch 123, 124 is thrown in or out.

Shaft 128 is longitudinally moved to and fro by suitable means, and for this purpose, the hub of gear wheel 133 is annularly grooved, and an operating lever 140 is connected thereto to so move the shaft.

Supported in the machine frame (Fig. 6) is a stub shaft 141, and loosely journaled thereon is a gear wheel 142, the hub thereof having an annular groove 143 formed therein, a shifting lever 144 cooperating therewith. A gear wheel 145 is fixed on the exterior end of shaft 122. By means of lever 144, gear wheel 142 is moved into and out of mesh with both gear wheel 103 and gear wheel 145, acting when in mesh as an idler or intermediate therebetween, and making a through or continuous drive from gear wheel 96 to gear wheel 145.

Referring now to the operation of the shown and described mechanism:

It will be recalled that gear wheel 100 and gear wheel 103 may be alternatively rotated or driven from the motor 82 by means, respectively, of clutches 87 and 93; also that the conveyer drive may optionally remain at rest or be driven in either direction from the gears 100 and 103, respectively, by means of clutches 101 and 104. The four clutches just referred to are operated by their respective levers 88, 94, 102 and 105.

When gear wheel 133 is thrown into mesh with gear wheel 100 by actuating lever 140, gear wheel 130 is also thrown into mesh with gear wheel 131.

The manner of operation of the foregoing is substantially as follows:—

To travel the machine forward:

When gear wheel 142 is in mesh with gear wheels 103 and 145, and clutch 124 is in mesh, the machine will travel forwardly or backwardly dependent on the direction of rotation of the motor. That is, with the connections as described, by running the motor in one direction or the other, the machine may be run either forward or backward as desired. If it is desired to run the conveyer when the machine is traveling forward, as in attacking a pile of coal resting on the mine bottom, this may be done by throwing

in clutch 101 or clutch 104, depending on the direction of rotation of the motor.

To turn the machine by operating the caterpillar treads in opposite directions:—

5 When gear wheels 133 and 130 are in mesh and clutch 124 is open and at the same time gear 142 is in mesh, the endless belt treads will travel in opposite directions and turn the machine. By reversing the motor the treads may be operated in the opposite direction.

10 To drive one endless belt tread while the other is at rest:—

15 Gear wheel 142 is moved out of mesh, and gear wheel 130 is moved into mesh, thus throwing clutch 124 out of engagement and clutch 87 is thrown in. Tread 81 will then be driven in either direction, dependent on the direction of rotation of the motor, while tread 80 is at rest. If clutch 87 be thrown out, and gear 142 is moved into mesh with gears 145 and 103, and clutch 93 is thrown in, tread 80 will be driven in either direction, dependent on the direction of rotation of the motor, while tread 81 is at rest.

20 Various other combinations including changes in the direction of drive or state of rest or motion of the conveyer and of the treads are possible and available, but need not be described in detail.

25 For the purpose of capacitating the machine for efficiently handling coal or other material lying loose on the floor or ground, the forward end of the frame is provided with an apron or plate 150, inclined upwardly from the floor at its forward end to the level of the conveyer at its rear or inner end. The side plates 9 and 10 cooperate therewith to guide the material, as best shown in Fig. 2. The traction treads can drive the machine forward while the conveyer at the same time is moving to convey the coal back, and the machine can be wheeled or backed, or traveled in any direction, with the conveyer moving or at rest, as desired. The side plates 9 and 10 will retain the coal from spilling sidewise. A car for receiving the coal is shown conventionally at 151 in Fig. 2, which may be attached during the loading operation to the frame by any suitable means, and may stand for any convenient means for receiving or disposing of the coal.

30 The invention is not limited to the precise forms of construction herein shown and described, but changes may be made therein without departing from the principles of the invention.

35 What I claim is:—

1. A coal handling-machine for use in narrow coal seams, including in combination, a low flat frame, an endless conveyer passing over and under the frame, endless traction treads alongside the frame and substantially coextensive longitudinally with

the said endless conveyer, and means for driving the endless traction treads independently.

2. A coal handling-machine including in combination a low, flat frame, an endless conveyer passing over and under the frame, endless traction treads engaging the floor at either side of the endless conveyer, and being substantially coextensive longitudinally therewith, means for driving the traction treads independently of each other, and means at the forward end of the machine for directing loose material to the conveyer.

3. A coal handling machine, comprising a low flat frame, an endless conveyer carried thereby, endless belt drives alongside said conveyer and substantially coextensive longitudinally therewith, the upper and lower reaches of the said conveyer and belts being on substantially the same level, respectively, a scoop at the front end of the machine for directing material onto the conveyer, and means for driving the said belts.

4. A coal handling machine, comprising a low flat frame, an endless conveyer carried thereby, endless belt drives at either side of said conveyer and substantially coextensive longitudinally therewith, and means for driving the said belts forwardly or backwardly, independently of each other.

5. A coal handling machine, comprising a low flat frame, an endless conveyer carried thereby, endless belt drives alongside said conveyer and substantially coextensive longitudinally therewith, the upper and lower reaches of the said conveyer and belts being on substantially the same level, respectively, a scoop at the front end of the machine for directing material onto the conveyer, and means for separately driving the conveyer and the belts.

6. A coal handling machine, comprising a low flat frame, an endless conveyer carried thereby, endless belt drives alongside said conveyer and substantially coextensive longitudinally therewith, the upper and lower reaches of the said conveyer and belts being on substantially the same level, respectively, a scoop at the front end of the machine for directing material onto the conveyer, means for driving the conveyer, and means for independently driving the said belts.

7. A coal handling machine, comprising a low flat frame, an endless conveyer carried thereby, endless belt drives alongside said conveyer and substantially coextensive longitudinally therewith, the upper and lower reaches of the said conveyer and belts being on substantially the same level, respectively, means for driving the conveyer, and means for independently driving the said belts forwardly or backwardly.

8. A coal handling machine including in combination a low, flat frame having longitudinally extending, channeled frame ele-

ments, endless traction belts located in the channels of the frame elements, an endless conveyer arranged between said frame elements, and means for driving the traction belts and the conveyer.

9. A coal handling machine including in combination a low, flat frame having longitudinally extending, channeled frame elements, endless traction belts located in the channels of the frame elements, an endless conveyer arranged between said frame elements, the upper reaches of the traction belts and the conveyer and the upper elements of the frame, being on substantially the same level, the corresponding lower parts of these members being similarly located at a lower level, and means for driving the traction belts and the conveyer.

10. A coal handling machine including in combination a low, flat frame having longitudinally extending, channeled frame elements, endless traction belts located in the channels of the frame elements, an endless conveyer arranged between said frame elements, a scoop at one end of the frame for guiding coal onto the conveyer, and means for driving the traction belts and the conveyer.

11. A coal handling machine including in combination a low, flat frame having longitudinally extending, channeled frame elements, endless traction belts located in the channels of the frame elements, an endless conveyer arranged between said frame elements, and means for driving the traction belts and the conveyer in either direction.

12. A coal handling machine including in combination a low, flat frame having longitudinally extending, channeled frame elements, endless traction belts located in the channels of the frame elements, an endless conveyer arranged between said frame elements, and means for driving the traction belts and the conveyer forwardly or backwardly independently.

13. A coal handling machine including in combination a low, flat frame, endless traction treads at each side of the frame for supporting it and for steering, an endless belt conveyer passing around the frame and located between the traction treads and substantially coextensive longitudinally therewith, the upper and lower reaches of the three endless elements being on substantially the same levels, respectively, means for driving the conveyer, and means for independently driving the traction treads in either direction.

14. A coal handling machine including in combination a low, flat frame, endless traction treads at either side of the frame for supporting it and for steering, an endless belt conveyer passing around the frame and

located between the traction treads and substantially coextensive longitudinally therewith, the upper and lower reaches of the three endless elements being on substantially the same levels, respectively, means for driving the conveyer, a scoop at the front end of the frame for guiding material onto the conveyer, and means for independently driving the traction treads in either direction.

15. A coal handling-machine having a low, thin, flat frame, close to the floor throughout, an endless belt conveyer filling substantially the entire space within the frame both crosswise and lengthwise, an endless traction tread arranged closely along each side of the frame and supporting it just clear of the mine floor, and means for selectively driving the endless treads in either direction.

16. A coal handling-machine having a low, thin, flat frame, close to the floor throughout, an endless belt conveyer filling substantially the entire space within the frame both crosswise and lengthwise, an endless traction tread arranged closely along each side of the frame and supporting it just clear of the mine floor, means for selectively driving the endless treads in either direction, and a motor for driving the treads, located at the rear of the conveyer unit.

17. A coal handling-machine having a low, thin, flat frame, close to the floor throughout, an endless belt conveyer filling substantially the entire space within the frame both crosswise and lengthwise, an endless traction tread arranged closely along each side of the frame and supporting it just clear of the mine floor, means for selectively driving the endless treads in either direction, and an apron at the front of the conveyer extending substantially from the floor upwardly and rearwardly to the forward end of the top reach of the conveyer.

18. A coal handling machine having a low, thin, flat frame, close to the floor throughout, an endless belt conveyer filling substantially the entire space within the frame both crosswise and lengthwise, an endless traction tread, substantially coextensive longitudinally with said endless belt conveyer, arranged closely along each side of the frame and supporting it just clear of the mine floor, a motor for driving the treads, located at the rear of the conveyer unit, and means for selectively coupling the treads with the motor for driving them in either direction.

In testimony whereof, I have signed my name to this specification.

RICHARD PEALE.
